UNITED STATES PATENT OFFICE.

JACQUES LUCIANI, OF PARIS, FRANCE, ASSIGNOR TO WILLY J. SOLMS, OF PARIS, FRANCE.

QUICK-FIRE GUN WITH MULTIPLE BARRELS.

1,363,608.

Specification of Letters Patent. Patented Dec. 28, 1920.

Application filed September 7, 1915. Serial No. 49,368.

To all whom it may concern:

Be it known that I, JACQUES LUCIANI, a citizen of the French Republic, residing at 100 Rue d'Amsterdam, Paris, France, have 5 invented a certain new and useful Quick-Fire Gun with Multiple Barrels, of which the following is a specification.

The present invention has for its object to provide a quick-fire gun with multiple 10 barrels. In this gun the barrels, which are of different lengths, are arranged in a plurality of rows or groups in any convenient manner. During the construction of the gun, the barrels are directed by means of an 15 appropriate device termed a "ballistic apparatus," in such a manner that their axes diverge to a greater or less extent and in different planes, in order to impart to the fire any desirable dispersion appropriate to 20 the effect sought to be obtained. A suitable device renders it possible to immobilize the barrels in the selected position, in such a manner that the fire is exceedingly regular. The calibers of all the barrels may be equal 25 or they may differ; the barrels may be brazed at their base, united by a hoop, screwed into a block or, generally speaking, they may be united and assembled in any appropriate manner. Each barrel may be 30 provided with a separate striker or the same striker may serve for all the barrels. Or there may be a series of strikers for each row of barrels and each series may be controlled independently of the others or simultaneously 35 therewith.

The accompanying drawings show, by way of example, a constructional form of this gun and some detail modifications;

Figure 1 is a side elevation showing the 40 gun as a whole;

Fig. 2 is a rear elevation thereof;

Fig. 3 is a plan view thereof;

Fig. 4 is a plan, to a larger scale, representing the details of the sliding cover 45 closing the mechanism;

Fig. 5 is a section on the line A—A of Fig. 4;

Fig. 6 is a detail view, to a larger scale, 50 of the mechanism controlling the aiming for elevation;

Fig. 7 is a longitudinal vertical section of the rear portion of the gun on the line B—B in Fig. 8;

Fig. 7^a is a vertical section on the line B'—B' in Fig. 7, viewed in the direction 55 indicated by the arrows;

Fig. 8 is a sectional plan representing the rear of the gun and showing the mechanism, the cover having been removed;

Fig. 9 is a vertical section on the line 60 C—C in Fig. 8, showing details of the cocking mechanism;

Fig. 10 shows details of the trigger;

Figs. 11 and 12 represent a loading plate, in front elevation and in section on the line 65 D—D in Fig. 11;

Fig. 13 shows the details of a striker;

Fig. 14 shows the details of an ejector, in section;

Fig. 15 is a plan view showing the assem- 70 blage of barrels with the ballistic apparatus in place for adjusting the said barrels;

Fig. 16 is a section to a larger scale at right angles to the barrels, on the line E—E in Fig. 15;

Fig. 17 is a plan view of the extremity of 75 the barrels with the ballistic apparatus in place, the cover of this apparatus being removed;

Fig. 18 is a vertical longitudinal section 80 of the extremity of the barrels with the ballistic apparatus in place;

Fig. 19 is a detail view showing a portion of the barrels and the device for locking or immobilizing them;

Fig. 20 is a diagrammatic view, in elevation, of the cocking mechanism, showing the position of these parts when the gun is uncocked;

Figs. 21, 22 and 23 are similar views 90 showing the position of the parts: (1) when the gun is cocked and ready for firing; (2) immediately after firing; (3) in an intermediate position, when, after firing, the mechanism being returned to the rear by 95 the displacement of the lever, the loading plate that has just acted falls and is replaced by a fresh plate filled with live cartridges;

Finally, Fig. 24 shows diagrammatically the arrangement of the strikers when the 100 three tiers of strikers are independently controlled.

In the embodiment of the invention here illustrated, the barrels 1 of the gun are, as shown more particularly in Figs. 1 and 3, 105 distributed in three horizontal tiers each

comprising eleven barrels; in this case therefore, the gun comprises thirty-three barrels; it will of course be understood that this number can be varied and that the gun may comprise a number of barrels quite different from that shown in the drawings. Similarly, the barrels may be differently distributed; for example, instead of being superposed, they may be arranged quincunx fashion, or staggered. The number of barrels is determined more particularly by the results aimed at and the caliber adopted.

As shown in Figs. 1 and 3, the barrels are of different lengths in each tier, the longest being preferably arranged at the center. This difference of length plays a considerable part in the precision of firing in preventing the projectiles from encountering each other in space.

20 In the method of construction illustrated, the barrels 1 (see Fig. 7) are screwed at their base into a block 2 in which are bored, in line with the barrels, the chambers 3 for the reception of the cartridges. The block 2 slides in the cradle 4 under the influence of the recoil. The block is guided in its movement in a slideway formed in the cradle and in which is engaged a projection 5 of corresponding section formed on the lower face of the block. In the example illustrated, the fixed slideway and the projection are dovetail in shape; obviously any other form of slide permitting of the longitudinal displacement of the block and preventing its displacement in the vertical direction might be adopted.

When the nest of barrels and the block 2 recoil in the cradle, the part 6 rigid with the block compresses the springs 7 serving as a brake. These springs return the block and the barrels into their initial position after firing. The tension of the springs 7 can be regulated by any appropriate means, for example by nuts 8 as shown in the drawings.

45 As already stated, the barrels are mounted in such a manner as to furnish a divergent fire. The divergence can be obtained in two ways;

1. By mounting the barrels, adjacent to the chambers, parallel with each other and separating them (by means of the ballistic apparatus) toward the muzzle until the desired divergence has been obtained;

2. By boring in the block 2 the holes intended for the reception of the barrels with the desired degree of divergence.

60 *Ballistic apparatus.*—The ballistic apparatus 9 (Fig. 15) is constituted by a steel frame 10 (Fig. 16); this frame, which is rectangular in form, serves as support for a series of vertical screws 11 and for a series of horizontal screws 12 which, as herein-after explained, permit of insuring the individual adjustment of each barrel for aiming for elevation and for direction.

Referring to Fig. 16, barrel *a* of the upper tier, it will be noted that this barrel is furnished with a block 13 extending throughout its entire length as shown in Fig. 17. The rod of one of the screws 12 passes through the upper part of this block; the housing for this rod in the block has a diameter slightly greater than that of the rod to permit of expansion; nevertheless the collars 14 provided upon the rod of the screw, outside its housing in the block clamp the block firmly in such a manner that from any displacement of the screw in the nut provided for it in the wall of the frame 10 a displacement of equal value of the barrel in a horizontal plane results. In proximity to the screw 12, the block 13 comprises another housing in which the rod of the vertical screw 11 is engaged, the portion of this rod thus housed in the base being smaller in diameter than the housing (again with the object of permitting play in expansion) and being comprised between two collars 15—15 (Fig. 18) which bear against the walls of the block in such a manner that a displacement of the barrel *a* in a vertical plane corresponds to each displacement of the screw 11 in the nut provided for it in the frame 10.

It will thus be noted that with the two screws 11 and 12 it is possible to displace the barrel *a* either in the vertical plane or in the horizontal plane, within the necessary limits. Consequently it is possible to adjust the position of all the barrels in each tier (eleven in the example illustrated) in such a manner as to obtain any desired dispersion of the group or sheaf of projectiles emitted by the gun.

It will be understood that the constructional details that have been set forth are given merely by way of example and it is obvious that, without departing from the spirit of the invention, other analogous devices might be adopted for acting upon the barrels in the horizontal and the vertical direction and thereby adjusting the gun in the course of its construction.

This essential adjustment having been effected during the construction of the gun, it is obviously important that it should be rigorously maintained no matter what shocks the gun experiences both during transportation and in actual firing. This result is attained by means of the immobilizing or locking device which will now be described.

Device for immobilizing the barrels.—In order to immobilize the barrels in the selected position of adjustment, after the barrels have been fitted, tapped holes are formed between two adjacent barrels to serve as nuts for fixing screws 16 (Fig. 19); these screws rigidly lock the barrels one to the other and prevent any subsequent displacement. Combined with these fixing

screws 16 are frames 17 forming securing bands arranged at intervals along the barrels; these frames assist in attaining the desired object by preventing any displacement 5 of the screws 16 during firing and during the transportation of the gun.

Although Fig. 1 shows the ballistic apparatus in position on the barrels, it will be understood that this apparatus does not 10 remain permanently upon the gun but can be removed as soon as the adjustment is finished and the barrels have been immobilized by means of the device illustrated in Fig. 19.

Fig. 19 applies to the case of square barrels; obviously the same devices would be applicable to round barrels.

The outer surface of the barrels may present appropriate flutings or projections serving to increase the outer surface and 20 thereby assist in the cooling of the gun during firing.

Loading, cocking and firing mechanism.— The cartridges required for loading the gun are arranged beforehand on loading devices 25 of the kind represented in Figs. 11 and 12. These devices consist of two plates 19 and 20 adapted to engage each other by sliding (see Fig. 12) and in which a number of holes corresponding with the number of 30 barrels are bored. The holes bored in the plate 20 present exactly the same diameter as the cartridge cases at their base; the holes in the plate 19, on the contrary, are of a smaller diameter which approximately 35 corresponds with that of the primer. It will be readily understood that, in these conditions, the cartridges can readily be passed into the holes in the plate 20 and that, by then causing the plate 19 to slide 40 behind the plate 20 as shown in Fig. 12, the cartridges are very efficaciously held, the rim on the base being clamped between the two plates 19 and 20. It will also be noted that, in passing through the holes in 45 the plate 19, the strikers can strike the primers of the cartridges 18 without impediment.

Behind the block of the barrels, the gun is continued by a breech forming a kind of 50 box 21 in which the mechanism is inclosed. A hole 22 is formed in the bottom of the box 21 immediately behind the block of the barrels (see Fig. 7); as hereinafter explained, after firing, the loaders carrying the spent 55 cartridges fall through this hole 22. A hole 23 of corresponding dimensions is formed upon the top of the breech.

The vacant space thus constituted behind the barrel block serves an important purpose 60 in the operation of the gun. It is into this vacant space that the cartridges pass downward during firing. This space also serves an important purpose as regards the cooling of the gun in facilitating the circulation of 65 the air around the barrels.

The cocking and firing mechanism is broadly constituted by a block 24, movable in slideways in the longitudinal direction. Two rods 25 are pivoted to this block, their rear ends being also pivoted to small cranks 70 26. At their other extremity these cranks 26 are keyed in some appropriate manner to a shaft 27. Finally, an operating and cocking lever 28 is keyed to this shaft outside the gun and preferably on the right hand side. 75 It will be readily understood that when the lever 28 is displaced forward or rearward the shaft 27 is caused to rotate, displacing the cranks 26 and consequently the rods 25 which cause the block 24 to move forward 80 or rearward.

In front of the block 24 is a plate 29 into which the strikers 30 are screwed; this plate is movable relatively to the block 24. The displacements of the plate 29 are guided by 85 the rods 31 passing through holes formed for this purpose in the block 24. Moreover, a central rod 32, fixed to the plate 29, passes through a hole in the block 24 and is prolonged behind this block by a part 33 ending 90 in a head 34 of a peculiar and characteristic form (see Fig. 9). In order to simplify the description the part 33 and its head 34 will be termed the "needle."

Around the rods 31 are arranged springs 95 35, the tension of which can be adjusted by means of threaded plugs 37 screwed into the block 24 and at the same time serving as guides for the rods 31.

Around the rod 32 is arranged a spring 36 100 100 which plays an essential part as regards firing.

Behind the breech is arranged a part 38 forming a kind of clamp between whose jaws the head 34 of the needle can engage. 105 As shown in Fig. 9 the jaws of the part 38 are of such a form that they can retain between them the part 34 (see Fig. 9). The part 38 can be advanced or drawn back in the breech by means of the adjusting device 110 constituted by the screw 39; an external milled head 40 permits of readily displacing the part 38; by means of this displacement the head 34 is immobilized sooner or later against the shoulders 41 of the jaws 38. It 115 follows that it is possible in this manner to modify the tension imparted to the spring 36 when the strikers are cocked by depressing the lever 28 right home. The tension of this spring 36 can also be adjusted by 120 acting upon the threaded plug 37' which screws into the block 24. Simple means are thus provided for rendering the operation of the gun more or less easy.

A cam 42 is arranged between the jaws 38. 125 In turning this cam by means of the lever 43 which serves as trigger, the jaws 38 are separated and the head 34 is consequently released.

In front of the plate of the strikers is ar- 130

ranged a plate 44 termed the impact or shock plate in which holes are bored for the passage of the strikers 30.

A frame 45 forming a slideway is fixed 5 upon the breech on the rear edge of the opening 23; the loaders filled with cartridges are arranged one above the other between these slideways.

When the parts occupy the position illustrated in Figs. 7 and 20, the lower loader 10 has descended and reached the position shown. In this position the loader rests upon the stop plate 46.

It will be understood that two or more 15 pins are provided on the under face of the block 24 and that these respectively engage in parallel slots in the plate 46 so that thus the plate 46 in its forward and in its rearward movement lags behind the movement 20 of the block 24. Thus the edge of the loading plate is supported by the forward edge of the plate 46 on the forward movement of the block 24 and the loading plate is only released as the cartridges enter the breech. 25 Similarly the front of the plate 46 comes into a position forward of the front face of the breech block 44 immediately after the breech block 44 has passed rearwardly to a sufficient extent to permit of the loading 30 plate carrying the discharged cartridges to fall through the space 22.

On each side of the striker plate are arranged claws forming extensions of the uprights of the loaders; these claws receive 35 the loader plate, guide it into the chambers for firing, bring it rearward when firing has taken place and allow it to fall at the moment at which they receive the next following loader plate.

40 Between the rows of chambers and around the latter are arranged the ejectors 47 constructed as shown in Fig. 14. Under the influence of the springs 47', the ejectors 47 press back the loader after firing and facilitate 45 its rearward movement.

The block 44 is rendered integral with the block 24 by being secured to lateral extensions of the block 24 as illustrated in the horizontal section, Fig. 8.

50 *Operation.*—The gun that has been described operates in the following manner:—

Between the slideways 45 the gun is provided with loader plates filled with cartridges, one of these plates occupying the 55 position shown in Figs. 7 and 20 and resting upon the stop plate 46. In order to fire, the lever 28 is pressed forward in such a manner as to cause it to occupy the position represented in Fig. 21. During this movement 60 the block 24 advances, pressing in front of it the striker plate 29; at the same time the shock or impact plate 44 and the loader plate advance. When the lever 28 is depressed right home, the loader plate occupies the

position shown in Fig. 21, that is to say the 65 cartridges have entered the chambers in the block 2.

The striker plate 29 participates in this movement only until the head 34 of the needle encounters the shoulders 41 of the 70 jaws 38 (see Fig. 21): from this moment, the block 24 continuing to advance, the spring 36 is compressed, which results in cocking the strikers. It will readily be understood that from this moment it is only 75 necessary to release the needle 33 in order simultaneously to release the plate 29 (and the strikers) thereby allowing the spring 36 to act. In extending, this spring (to whose action that of the two springs 35 is cumulative) vigorously presses the plate 29 with its strikers against the bases of the cartridges, thereby firing them. This result is obtained by acting upon the trigger 43 which serves to separate the jaws under the 80 influence of the cam 42. Fig. 22 shows the position of the parts at this moment; as shown in this figure, the needle has escaped from the jaws and the striker plate has moved away from the block 24, the extremity of the strikers being in contact with the bases of the cartridges. 85 90

In order to fire the next round it is only necessary to draw back the lever 28. During this movement the claws in which the loading plate is engaged laterally bring this plate rearward; when the whole reaches the position shown in Fig. 23, the plate carrying the cartridges that have just been fired falls through the orifice 22, the stop plate 46 having been shifted to one side by striking the rear face of the block 2 (see Fig. 23). During the continuance of the rearward movement of the lever 28 a moment is reached at which the next following 100 loading plate (see Fig. 23) ceases to be retained by the upper flange of the breech; it then falls between the slideways and occupies the position represented in Fig. 20. At the same time, it will be understood, the block 24 has returned to the position shown in Fig. 20, the needle has separated the jaws and has come between them as indicated in Figs. 20 and 23. The gun is now ready for 105 firing again; in order to re-fire it is only necessary to bring the lever 28 right home to its forward position and act upon the trigger 43. 110 115

In the description given above it has been assumed that all the strikers 30 are mounted 120 on a single plate 29 and that consequently by acting upon the trigger a number of shots equal to the number of barrels of which the gun is composed is fired simultaneously. It will be understood that means 125 can be provided which permit of firing only a portion of the cartridges. Thus, for example, the strikers might be arranged in

three rows of tiers corresponding to the three rows of barrels. Fig. 24 shows this construction diagrammatically.

In this case there is a single block 24 and 5 three striker carrying plates (29', 29" 29''). To each of these plates corresponds a needle (34', 34'', 34'') engaging between jaws (38', 38'', 38''). An independent cam and trigger corresponds to each of the jaws.

10 With this arrangement, by acting upon the triggers one after the other, it is possible to fire each row of barrels in succession. It is also possible, by acting upon all three 15 triggers simultaneously, to fire all the shots simultaneously as with the arrangement previously described.

Aiming mechanism.—At its lower part the gun cradle is continued by two lugs 49 bored for the passage of the shaft 50. The gun as 20 a whole is able to turn about this shaft for aiming for elevation. This rotation is obtained by acting upon the handwheel 51 keyed upon a shaft 52 at the other extremity of which is arranged an endless screw 53 25 meshing with a toothed sector 54 keyed upon the shaft 50. The shaft 52 is mounted at the side of the breech (see Fig. 3) and turns in the bearings 55.

It will be readily understood that, as the 30 sector 54 is fixed, by rotating the handwheel 51 the endless screw 53 is caused to roll around the sector and that this causes the rotation of the whole around the fixed shaft 50. In this manner the gun is aimed for 35 elevation. A divided sector 56 moves in front of a hand 57 so that the angle of elevation obtained can be determined with precision. A fixing screw operated by means of a handwheel 58 serves to lock the gun in 40 the position selected.

For aiming for direction the gun pivots around a vertical trunnion upon which the shaft 50 is fixed; this trunnion turns inside the foot 59 and is brought to rest in the 45 selected position by means of a set screw operated by the handwheel 60.

The base 61 of the trunnion turns upon a part of corresponding form constituting the upper portion of the foot 59; upon the outer 50 surface of this upper part are marked divisions over which moves an index 62 fixed to the base 61. A spherical air bubble level 63 is arranged upon the sliding cover 64 (Figs. 4 and 5) in which is formed a window 65 for the passage of the trigger 43. In combination with the index 62, this level 66 serves to insure both the horizontality of the gun in the transverse direction and the precise adjustment for direction in accordance with the firing instructions. Two perpendicular lines intersecting at the center are engraved on this level and also a certain number of equidistant concentric circles.

In firing operations, several of these guns 65 are arranged parallel one with the other at

appropriate distances. The guns being thus arranged equidistant from and parallel one with the other divergent streams of projectiles are obtained; these streams or jets impinge upon each other at a distance from 70 the muzzles which depends on the one hand upon the adjustment adopted for the divergence of the barrels and on the other hand upon the interval adopted in the field between the various guns at the commencement 75 of firing.

I claim:—

1. A quick-fire gun of the class described comprising a plurality of barrels, a breech portion to which the barrels are connected 80 and having a vertical passage therethrough, guide means disposed at said passage to receive a cartridge carrier, an impact plate arranged to move along the breech and to shift the loaded carrier forwardly until the cartridges thereof are introduced into the barrels, means arranged to support the carrier during the movement aforesaid and displaceable to permit the carrier to fall through the passage when the cartridges 85 have been fired, and means for shifting the impact plate forwardly and rearwardly to produce continuity of firing of the gun.

2. A quick-fire gun of the class described comprising a plurality of barrels, a breech 95 portion to which the barrels are connected and having a vertical passage therethrough, guide means disposed at said passage to receive a cartridge carrier, an impact plate arranged to move along the breech and to shift 100 the loaded carrier forwardly until the cartridges thereof are introduced into the barrels, means arranged to support the carrier during the movement aforesaid and displaceable to permit the carrier to fall 105 through the passage when the cartridges have been fired, strikers arranged in rear of the impact plate in position to impinge each of the cartridges mounted in the carrier, means for shifting the impact plate and 110 strikers forwardly and rearwardly of the breech, and means for cocking said strikers as an incident to the movement of the last mentioned means.

3. A quick fire gun of the class described, 115 comprising a plurality of barrels, a breach portion to which the barrels are connected, a sliding block carrying the firing pins, a sliding breech block adapted to carry the loading plate, means operated by a single lever to effect the rectilinear movement of the said breech block, sliding block and firing pins, means for holding and releasing the firing pins, and a loading plate formed of two plates, in one of which plates holes are 120 formed for the reception of the cartridge cases, the other plate sliding over the first and serving to hold the rims or edges of the cartridge cases at the base, substantially as 125 described.

4. A quick fire gun of the class described, comprising a plurality of barrels, a breech portion to which the barrels are connected, a sliding block carrying the firing pins, a sliding breech block adapted to carry the loading plate, means operated by a single lever to effect the rectilinear movement of the said breech block, sliding block and firing pins, and a cocking device constituted of a

needle shaped part engaging two jaws with 10 which the said needle shaped part engaged until the moment of firing, substantially as described.

JACQUES LUCIANI.
